UNITED STATES PATENT OFFICE.

ADOLF B. SCHLEICHER, OF PASADENA, CALIFORNIA.

DESIGN FOR A TIRE.

55,087.

Specification for Design.

Patented May 4, 1920.

Application filed January 28, 1920. Serial No. 354,735. Term of patent 7 years.

To all whom it may concern:

Be it known that I, ADOLF B. SCHLEICHER, a citizen of the United States, residing at Pasadena, in the county of Los Angeles and State of California, have invented a new, original, and ornamental Design for Tires, of which the following is a specification, reference being had to the accompanying drawing, forming part thereof.

In the drawing,

Figure 1 is a cross-sectional view of a por-

tion of a tire showing my new design, and Fig. 2 is a face view of the tire shown in Fig. 1, showing my new design.

I claim:

The ornamental design for a tire as shown.

ADOLF B. SCHLEICHER.
